UNITED STATES PATENT OFFICE.

JONATHAN BRASSFIELD, OF PEORIA, ILLINOIS.

FUMIGATING DEVICE.

1,088,122.

Specification of Letters Patent. Patented Feb. 24, 1914.

Application filed July 2, 1912. Serial No. 707,353.

To all whom it may concern:

Be it known that I, JONATHAN BRASSFIELD, a citizen of the United States, residing at Peoria, in the county of Peoria and State of Illinois, have invented certain new and useful Improvements in Fumigating Devices; and I do hereby declare that the following is a full, clear, and exact description of the invention, which will enable others skilled in the art to which it appertains to make and use the same.

This invention relates to a fumigating apparatus particularly of a type that includes a closed vessel in which to place the articles to be fumigated together with the fumigating chemicals.

The object of the invention is to provide an air-tight receptacle in which to place articles to be fumigated and particularly adapted for use in such places as hospitals, almshouses and the like.

To the end that the invention may be thoroughly understood I have provided the accompanying drawing in which:

Figure 1 shows the device in vertical section. Fig. 2 is a plan of the upper portion of the body of the device on a greatly reduced scale. Fig. 3 is a plan of a diaphragm or plate located within the body and also greatly reduced in scale.

The apparatus comprises a body A which, for convenience in manufacturing, is cylindrical in form, but which may be of any other shape such as square, for example, and open at its upper and lower ends. The upper end of the body is provided with an inner flange 2 and secured to said body is an outer flange 3 the flanges together forming a channel for the reception of a liquid. A' is a section somewhat like the body A and adapted to seat at its lower end in the said channel. Encircling the upper end of the said section A' is a flange B forming with the said section a channel for a liquid. C is a lid having a depending flange D adapted to enter between the body of said section A' and the flange B and which may rest upon the latter as shown.

The bottom of the apparatus consists of a plate E having an upturned annular flange F within which to seat the body A as shown. Spaced inward from the flange is a ring or annulus G secured at its lower edge to the

plate in a fluid tight manner so that the space between it and the flange F will hold a liquid. The diameter of the body A is somewhat smaller than the diameter of the flange F and somewhat larger than the diameter of the ring G so that when set in position it will lie between the two parts mentioned, as clearly illustrated.

H is a receptacle for a fumigating chemical which is seated upon the plate E and is preferably provided with a conical lid J which hangs upon the walls of said receptacle and depends within the latter and is provided centrally with a hole K. Said receptacle is provided with a series of holes L in its wall the purpose of which will be understood presently. M is a pipe one end of which overhangs the hole K in the said conical lid J, its other end extending outside the vessel A and this may carry a funnel N into which to pour a fumigating chemical and the opening of the pipe is provided with a stopper O.

Somewhat above the receptacle H is a plate or diaphragm P secured within the body and this may extend the full diameter of said body if desired, or it may be of smaller diameter. Said diaphragm is perforated except at its central portion, as indicated in Fig. 3, which in being imperforate prevents a splashing or upward movement of the fumigating liquid into the upper compartment of the body during chemical reactions.

Near the top of the sections A and A' is a series of bars Q, see Fig. 2, supported upon members X secured to the walls of the sections A, A', said bars being either stationary or removable, and upon which the articles to be fumigated are placed or from which they may be suspended. However, the said bars may occupy a position within the body A, and any suitable form of supports may be provided for each of them, see Fig. 1.

Secured to the wall of the body A preferably near the bottom is a box or inclosure a the interior of which communicates with the interior of the said body A as shown. In the wall of the box is an aperture d covered at the outside by a valve b carried by a spring C.

Attached to the wall of the apparatus

near the top, for example, is a valve box A². This may be carried by the section A' as shown or by the body A as may be desired. Said box communicates with the interior of the apparatus and has an aperture c closed within the box by a valve A³ carried by a spring A⁴.

The valves b A³ may be placed directly on the walls of the apparatus if desired, the boxes a A² being used merely in order to provide a flat surface for the valve instead of a curved surface such as would be provided by the body of the apparatus if the latter is cylindrical in form. If the body 15 has a flat surface, however, such as would be provided, for example, by making said body square in form, the boxes would not be required.

In using the device the receptacle H is first charged with the crystals or other forms of materials for producing the fumes, then the body A is set in position upon the plate E, after which the garments, or other articles, are suspended in the body. After 20 placing the lid C in position, the joints are sealed by placing water in the upper channel formed by the flange B and the body A, in the lower channel between the flange F and the ring G and in the channel 25 formed by the flanges 2 and 3. Now by removing the plug O any proper chemical to produce reaction upon the material in the receptacle H is poured into the funnel N and this finds its way to the said receptacle 30 H through the pipe M and the aperture K of the lid J. The fumes from the chemicals now pass out through the hole K or apertures L of the receptacle H up through the apertures P' of the diaphragm P into the body to fumigate the articles within the 35 body.

The device is of considerable value in hospitals, jails, workhouses, almshouses and like institutions where garments or bedding infested with vermin or with disease germs are to be rendered clean and serviceable, and by constructing the device of large size considerable quantities of bedding, clothing and the like can be treated, as is evident. 45 The device is also well adapted for special use as, for example, in the fumigation of the garments of nurses, doctors, and their assistants in hospitals and the like.

It is observed that water, oil, or other 55 liquid, that may be employed for sealing purposes will absolutely prevent the escape of fumes causing no annoyance therefore to persons working about the device. As an additional safeguard against leakage of 60 fumes water or other liquid can be poured into the funnel N to seal any slight opening that may exist around the plug O. The diaphragm or plate P, as before stated, has a central imperforate portion directly above

the receptacle H so that in case fluid is 65 thrown upward by chemical reaction it will not be thrown upon the clothing being fumigated.

The receptacle existing within the ring G on the bottom E may, of course, be used 70 for the chemicals in place of the receptacle H, if desired, although by using the latter the device may be more readily cleaned.

The apparatus is capable of ready enlargement by adding as many of the sections 75 A' as desired so that articles of great size or length can be accommodated.

The gas formed by the chemicals will increase the pressure in the apparatus slightly above atmospheric pressure and in order to 80 enable the air to escape under this increase I provide the valve b through which the air can readily escape. Again, in case a partial vacuum forms in the apparatus due to condensation or other causes the valve A³ 85 serves to admit the outer air to equalize the pressure.

Having thus described my invention, I claim:

1. In a fumigating apparatus the combination of an air tight receptacle for the article to be fumigated, a vessel to receive a disinfecting material having a perforate wall, a funnel shaped cover-plate for the same having a single opening, and a conduit extending into the receptacle and terminating at one end above said cover-plate and terminating at its other end outside the receptacle. 90

2. In a fumigating apparatus the combination of an air tight receptacle to receive the articles to be fumigated and a disinfectant, there being an opening in the lower part of the receptacle, a valve covering and closing the same adapted to open outward, 100 there being an opening in the upper portion of the receptacle, and a valve covering and closing the same and adapted to open inward, said valves being constructed so as to maintain approximately atmospheric pressure 105 within the receptacle. 110

3. In a fumigating apparatus the combination of a closed receptacle for receiving the fumigating material and the articles to be fumigated, said receptacle having two 115 openings therein, a valve adapted for normally closing each opening, one of them adapted to open inward and the other adapted to open outward, said valves being constructed and arranged so as to maintain 120 approximately atmospheric pressure within the receptacle.

4. In a fumigating apparatus the combination of a receptacle for receiving the fumigating material and the articles to be fumigated, the same having open ends, a receptacle for containing a liquid and forming a closure for the lower end of the receptacle 125

and into which said receptacle is adapted to be seated, an air tight closure for the upper end of the receptacle, the receptacle having two openings therein and a valve 5 to close each opening, both valves adapted to normally close the openings, one of them adapted to open outward and the other adapted to open inward, said valves being constructed and arranged so as to maintain

approximately atmospheric pressure within 10 the receptacle.

In testimony whereof I affix my signature, in presence of two witnesses.

JONATHAN BRASSFIELD.
